UNITED STATES PATENT OFFICE.

CHESTER S. LEONARD, OF PHILADELPHIA, PENNSYLVANIA, ASSIGNOR
OF ONE-HALF TO ELLSWORTH L. WARD, OF PHILADELPHIA, PENN-
SYLVANIA.

PNEUMATIC DRILL.

No. 800,224.

Specification of Letters Patent.

Patented Sept. 26, 1905.

Application filed February 23, 1905. Serial No. 246,928.

To all whom it may concern:

Be it known that I, CHESTER S. LEONARD, a citizen of the United States, residing at Philadelphia, in the county of Philadelphia and State 5 of Pennsylvania, have invented a new and useful Portable Multicylinder Pneumatic Drill, of which the following is a specification.

This invention relates to that class of driving motors or mechanisms in which air or steam under pressure is used to produce reciprocating rectilinear motion of parts within cylinders, the said reciprocations being transformed into rotary motion and this motion used for operating tools in their work performance. Its objects are, first, those sought in ordinary mechanisms of the same class—symmetrical construction, compactness, simplicity, lightness, and freedom from vibration, friction, and noise; second, to provide a mechanism of unusual strength and stability, yet comprised of a minimum number of parts and each part so designed as to be readily amenable to rapid and economical means of production and construction; third, to provide a 25 mechanism that can be easily handled and operated by inexperienced persons without danger, which is not liable to get out of order except by untoward accident, and which is readily portable; fourth, to provide in such mechanisms means for using the driving force expansively and to the best advantage without the use of stuffing-boxes, fly-wheels, or crank-shafts commonly employed; fifth, to provide means of reversing the direction of rotation 35 of work-spindle at will; sixth, to provide for such mechanisms a positive feed operated without manual labor and which is under the complete and ready control of the operator. With these objects in view this mechanism is 40 hereinafter fully described, and shown in the accompanying drawings, forming part of this specification, and in which—

Figure 1 is a general view in side elevation. Fig. 2 is a vertical section on the center line of 45 Fig. 1. Fig. 3 is a section of the removable upper guiding-handle. Fig. 4 is a partial plan view of the same. Fig. 5 is a section on line *a a* of Fig. 2, showing the spindle-driving gears. Fig. 6 is a cross-section on line *b b* of Fig. 50 7 with the feed-piston removed. Fig. 7 is a vertical section on line *c c* of Fig. 6. Fig. 8 is a fragmental section on line *d d* of Fig. 6. Fig. 9 shows an alternative method of uniting the upper and lower portions of the case.

Fig. 10 is a section taken on line *e e* of Fig. 2. 55 Fig. 11 is a cross-section on line *f f* of Fig. 2. Fig. 12 is a vertical section on line *g g* of Fig. 10. Fig. 13 is a vertical section on line *h h* of Fig. 10. Fig. 14 is a view of the piston-valve yoke looking from the center of the mechanism. 60

Similar characters refer to similar parts throughout the several views.

The lower main frame (represented by the numeral 1) has secured to it by screw-threaded connections or bolted flanges the upper 65 frame 2, having in turn secured by bolts the cover 3, the upper side of which has an upturned annular ring 3^a, screw-threaded to receive the feed-cylinder 4 or, in substitution thereof, the guiding-handle 5, which is interchangeable with the feed-cylinder 4. Other means of manipulating the motor are provided for by the handles 6 and 6^a, which are attached on opposite sides of the frame 2. On one side of the main frame, between and in the same 70 plane as the handles 6 and 6^a, is an inlet-valve 7 for controlling the admission of air or steam from its source of supply through a flexible hose 8. The said inlet-valve 7 is so arranged that the current of air or steam may be directed to the ordinary inlet-ports or to the exhaust-ports at will, which arrangement is made use of in reversing the direction of rotation of the motor. The said current after 75 passing through valve 7 is admitted to the annular passage-way 9, cored in the upper part of the frame 2. From thence it is taken through the ports 10 10^a 10^b 10^c into the valve-chambers 11 11^a 11^b 11^c, which contain the piston-valves 12 12^a 12^b 12^c, the action of which 80 will be taken up later. From the valve-chambers 11 11^a 11^b 11^c the current is admitted through the passages 44 44^a 44^b 44^c into the cylinder 13 13^a 13^b 13^c, operating on the pistons 45 45^a 45^b 45^c therein. From thence it 85 is exhausted through the upper portion of the valve-chambers 11 11^a 11^b 11^c to the circuitous passage 46, cored in the cover 3, and conducted through the passage 47, cored in the side of the upper casing 2, connecting with 90 the valve 7 through the port 48, from whence it escapes into the atmosphere at 49. It is evident that the direction of the current may be reversed by the action of the valve 7, so as to cause the motor to work in a reverse direction. 95

The pistons 45 45^a 45^b 45^c are connected by the piston-rods 14 14^a 14^b 14^c, pivotally at- 100

tached thereto at one end and in like manner connected to the crank-pins 15 15^a 15^b 15^c, integral with the crank-disks 16 16^a 16^b 16^c, which are rotatable with their shafts 17 17^a 17^b 17^c in ball-bearings 18 18^a 18^b 18^c, set in the casing 2 at its joint with the lower portion 2^a, the said portion being bolted together by the bolts 43, as indicated in Fig. 11. On the opposite ends of the said shafts 17 17^a 17^b 17^c are secured the bevel-gears 19 19^a 19^b 19^c, all of which are adapted to mesh with the large bevel-gear 20, centered on the upper portion of the spindle 37, and having interposed between, the sleeve or bushing 37^a, while the thrust is taken on the ball-bearing 20^a. Also in mesh with the bevel-gear 20 are the valve-operating bevel-gears 21 21^a 21^b 21^c, centered on their shafts 22 22^a 22^b 22^c and set in ball-bearings 23 23^a 23^b 23^c, located midway between the driving-gears 19 19^a 19^b 19^c. The inner ends of the said shafts 22 22^a 22^b 22^c carry disks 24 24^a 24^b 24^c, having roller-studs 25 25^a 25^b 25^c, adapted to work in the Scotch yokes formed within the lower ends of the piston-valves 12 12^a 12^b 12^c in such manner as to convey rectilineal motion only.

Evidently the matter of timing the relative position of each piston-valve with reference to its working cylinder may be readily accomplished by causing the gears attached to each to be properly meshed with the gear 20, and it is also evident that each set of gears may also likewise be adjusted to any other set or sets.

It is noticeable that all the cylinders and valveways are bored parallel to the central opening and directly in the material of the upper main frame 2, thus making the construction of the simplest order and avoiding a multiplicity of parts. The central opening contains a plunger-rod 26, connected at its upper end to a piston-head 27, fitted to the feed-cylinder 4, which forms the upper part of the apparatus.

Extending through the cover or head of the cylinder 4^a is a conical pointed projection 26^a of the plunger-rod 26. The said piston-head 27 is fitted with a cup-packing 27^a, and air or steam is admitted at the opening 28, formed on one side of the cover 3 and upper frame 2.

In the passage-way is provided a stop-cock 29, which is operated by the handle 30, said cock being provided with the usual cross-passage, so that when the handle is turned the position of the passage will control the supply of air, limiting it as may be desired. A very little amount of opening will give a corresponding slow upward movement of the feed piston-head 27, thereby imparting a downward movement to the mechanism in the casing, as the point of the piston-spindle 26^a is presumed to be stationary. The rapidity of the movement is readily regulated by the cock 29. When the piston-head 27 shall have

reached nearly to the upper end of its stroke, the openings 31 in the plunger-rod 26 will have reached the level of the bottom of the cylinder 4, and the compressed current of air or steam will enter therein, passing through the channel 32 and out at the holes 33, thus allowing the pressure to become equal on each side of the piston-head 27. Now if the current be cut off by the cock 30 the piston-head will be unsupported and move downward to the bottom of the cylinder by gravity, assisted by the expansion of the air or steam which has been admitted through the holes 31, passage 32, and holes 33 to the upper side of the piston-head 27. When the piston-head 27 has reached the bottom of the cylinder 4, the air or steam which has been admitted to the upper side of the piston-head 27 will escape through the holes 33, passage 32, and holes 31 into the annular chamber 50, from whence it is conducted by the passages 51 51^a 51^b 51^c into the circuitous passage 46 and exhausted therefrom with the exhaust from the cylinder.

The lower end of the plunger 26 has an inserted plug 34, adapted to strike against a knock-out pin 35. The said pin 35 is maintained in its normal position by the cross-pin 36, set in the sleeve 37 and working freely in a slot formed in the knock-out pin 35.

The hub of the gear 20 extends downwardly and has centered on it a pinion 38, meshing with the spur-gear 39, which is rigidly attached to the pinion 40, both of which revolve freely on the stud 41, set in the casing 1. The pinion 40 is adapted to mesh with the spur-gear 42, centered on and meshing with the tool-holding spindle 37, the thrust of which is taken on the ball-bearing 37^b.

The feed-cylinder 4, together with the piston-head 27, plunger-rod 26, and their attached parts, may be entirely removed from the top of the cover 3 and the interchangeable handle 5 used in its place, whenever it may be desired, as in performing certain work with the apparatus.

It is understood that the form of the casing or the location of the tool-holding spindle is immaterial to the scope of this invention and may be varied from that shown without departing from the spirit of the invention.

Having thus described my invention, what I claim, and desire to secure by Letters Patent, is—

1. In a device of the class described, the combination with the casing and driving-spindle, of a plurality of cylinders formed integrally within the said casing parallel with the driving-spindle and equidistant thereto; pistons in the said cylinders, crank-disks, pivoted connecting-rods connecting the disks and pistons, bevel-gears centered on said disks, a larger bevel-gear centered on the said spindle meshing with each of the said gears, cy-

lindrical valve-chambers formed in the said casing in relation to their cylinders, slideable valves working therein, crank-disks connected to the said valves, and crank-operating bevel-gears arranged each between the said piston-gears and meshing with the said larger bevel-gear, all substantially as shown and described.

2. In a device of the class described, the combination with a sectional casing and central driving-spindle, of a plurality of equidistant, symmetrically-positioned cylinders, formed in the body of the casing, parallel with the driving-shaft, pistons within the said cylinders, crank-disks having bearings in the body of the said casing, pivoted connecting-rods between the disks and pistons, bevel-gears centered on the said disks, a larger bevel-gear centered on the said driving-spindle meshing with each of the said gears, valve-chambers formed in the said casing, slideable piston-valves therein, valve-operating bevel-gears journaled within the said casing meshing with the said larger bevel-gear, connection between the valves and bevel-gears, an inlet-valve controlling the admission of driving fluid, an annular passage-way formed in the casing-cover communicating with each of the valve-chambers and an exhaust-opening

leading therefrom, both inlet and outlet ports being controlled by the said piston-valves, all substantially as shown and described.

3. In a device of the class described, the combination with a casing having inlet and exhaust ports, of a spindle vertically mounted therein, a driven bevel-gear mounted on said spindle, a plurality of driving bevel-gears journaled above said driven gear and adapted to mesh therewith, shafts and crank-disks thereon, connected to each of the driving bevel-gears, a plurality of cylinders formed in the casing, pistons therein, connecting-rods between the pistons and crank-disks, inlet-ports provided for each cylinder, valveways formed adjacent to each cylinder, piston-valves working therein, valve-operating bevel-gears meshing with the driven bevel-gear, shafts, and crank-disks and connecting members between the disks and valve-pistons, all substantially as shown and described.

In testimony whereof I have signed my name to this specification in the presence of two subscribing witnesses.

CHESTER S. LEONARD.
